(57) **CLAIM**

The ornamental design for a laminating cartridge, as shown and described.

DESCRIPTION

FIG. 1 is a front perspective view of a laminating cartridge embodying the present invention.

FIG. 2 is a rear perspective view of the laminating cartridge of FIG. 1.

FIG. 3 is a front view of the laminating cartridge of FIG. 1. FIG. 4 is a rear view of the laminating cartridge of FIG. 1. FIG. 5 is right side view of the laminating cartridge of FIG. 1.

FIG. 6 is a left side view of the laminating cartridge of FIG. 1.

FIG. 7 is a top view of the laminating cartridge of FIG. 1; and,

FIG. 8 is a bottom view of the laminating cartridge of FIG. 1.

The broken lines illustrate environment and form no part of the claimed design. The alternating long-short dashed lines in FIGS. 1 and 3 indicate boundaries separating claimed and non-claimed portions of the design.

1 Claim, 6 Drawing Sheets
